United States Patent Office.

GELSTON SANFORD, OF BERGEN, NEW JERSEY.

Design No. 4,452, dated November 1, 1870.

DESIGN FOR CYLINDER AND FRAME OF STEAM-ENGINE.

The Schedule referred to in these Letters Patent and making part of the same.

To all whom it may concern:

Be it known that I, GELSTON SANFORD, of Bergen Point, in the county of Hudson and State of New Jersey, have invented a new Design for the Cylinder and Frame of a Steam-Engine; and I do hereby declare that the following is a full, clear, and exact description of the same, reference being had to the accompanying drawing forming part of this specification, and in which—

Figures 1 and 2 represent side views, in perspective, from positions at right angles to each other, of a steam-engine frame with its attachments, as embraced by my design.

Similar letters of reference indicate corresponding parts.

The cylinder A is of square form externally, and has projecting up from it, on opposite sides, parallel therewith, the side frames B B, which are of tapering-shape in direction of their width, and of a uniform thickness at their edges, except at top, where they are spread out, as shown at *a a*, at either end of semicircular swells *b b*, that serve as bearings for the engine-shaft.

The square exterior of the cylinder terminates at

the bottom with a lower flange, *c*, which rests upon the feed water-heater C.

This heater C is also of square or rectangular shape, and is provided with a base flange, *d*, united to its body by a molding, *e*.

Arranged on the one side of the cylinder, and of a corresponding width therewith, is the steam-chest E, to the cover of which is attached, by a web, *f*, the pump-cylinder F, which is arranged to occupy an oblique position relatively to the base of the entire frame, as represented in fig. 1.

What I claim as my invention, and desire to secure by Letters Patent, is—

1. The design and configuration of the cylinder-portion A, side-frames B B, and feed water-heater C, when combined, as herein shown and described.

2. The design and configuration of the steam-chest E, its cover E', and the pump-cylinder F, as herein represented and described.

GELSTON SANFORD.
